A. R. TRIST.

FABRIC PARTICULARLY APPLICABLE TO THE MANUFACTURE OF RING PACKING FOR GLANDS.
APPLICATION FILED FEB. 16, 1922.

1,414,001.

Patented Apr. 25, 1922.

ARTHUR RONALD TRIST
INVENTOR;

By *Oto Mink*
his Attorney.

UNITED STATES PATENT OFFICE.

ARTHUR RONALD TRIST, OF LONDON, ENGLAND.

FABRIC PARTICULARLY APPLICABLE TO THE MANUFACTURE OF RING PACKING FOR GLANDS.

1,414,001.

Specification of Letters Patent. Patented Apr. 25, 1922.

Application filed February 16, 1922. Serial No. 536,903.

To all whom it may concern:

Be it known that I, ARTHUR RONALD TRIST, a subject of the King of Great Britain and Ireland, residing at Dinneford House, 12 Clipstone Street, London, England, formerly of Coronation House, 4 Lloyds Avenue, London, England, have invented new and useful Improvements in and Relating to Fabrics Particularly Applicable to the Manufacture of Ring Packings for Glands, of which the following is a specification.

This invention relates to improvements in fabrics and has particular reference to fabrics employed in the production of articles involving superimposed layers of sheet material such as packing for glands, hose piping, pneumatic tyres and belting, and has for its object the production of an improved sheet material and a method of manufacture whereby such material may be produced in a very expeditious and economical manner said material being of a character particularly well adapted to resist tensional stress 25 in a direction other than that of the warp and weft.

In building up articles of ring form from superimposed layers of fabric it is well known that to obtain the desired formation 30 the fabric must be cut on the bias and that as a result the article produced may be easily deformed.

The invention consists in the arrangement of a plurality of auxiliary strands upon a 35 fabric comprising interwoven warp and weft threads said auxiliary strands being attached to the fabric by means of a suitable agglutinant said auxiliary strands being so disposed in the finished article that 40 they are particularly well adapted to resist tensional stress and means whereby such strands may be placed in position.

Referring to the drawings, which form part of this specification,

Fig. 1 illustrates a piece of woven fabric 45 having auxiliary threads substantially disposed at 45° to warp and weft.

Fig. 2 diagrammatically illustrates one method by which the improved sheet material can be expeditiously manufactured.

Referring to Fig. 1 of the drawings it will be seen that the auxiliary strands *a* are disposed in angular relation to the warp *b* and weft *c* and when the fabric comprised by 55 that warp and weft is impregnated with an

agglutinant the strands *a* may be similarly impregnated means being provided whereby the auxiliary strands *a* are pressed into close association with the warp *b* and weft *c* to produce a compound sheet material having smooth surfaces. 60

The particular angular relation of the auxiliary strands *a* to the warp *b* and weft *c* depends upon the way in which the bias cut compound sheet material is employed, 65 said strands *a* being so dispositioned that in the finished article they will assist the warp and weft in resisting tensional stress.

Assuming that the sheet material required is to include woven fabric cut on the 70 bias so as to have the warp *b* and weft *c* disposed at 45° to the cut the auxiliary strands *a* are disposed substantially at 45° to the warp *b* and weft *c*.

To form such a compound sheet material 75 the method diagrammatically illustrated in Fig. 2 may be employed. The impregnated fabric *d* is first wound in uncut condition from a roll *e* on to a mandrel *f* with an angular pitch of 45° the edges of the impregnated fabric *d* being arranged to abut. The auxiliary impregnated strand *a* is wound from the reel *g* on to the impregnated fabric *d* on the mandrel *f* at such a pitch as will produce the required spacing, pressure and 80 other treatment by means of rollers (not shown) being employed to embed the auxiliary strand *a* in the fabric *d* in close association with the warp *b* and weft *c* the whole being included in the impregnating 85 material so as to produce a compound impregnated sheet material having smooth surfaces. 90

The cylinder of compound sheet material is now cut along the junction line at about 95 the point *h* so as to produce a strip of compound sheet material similar in dimension and shape to the impregnated fabric originally employed.

By this means it will be seen that the auxiliary strands *a* are in spaced parallel relation to one another and substantially angularly disposed at 45° to the warp *b* and weft *c*. 100

When this compound sheet material is cut 105 on the bias at 45° as at *i* and *k* it will be obvious that the warp *b* and weft *c* of the woven fabric will be at 45° to the cut edge and the auxiliary strands *a* will be at 90° to such edge so that when the compound fab- 110

ric is made up into a formation involving superposed layers the auxiliary strands *a* will be substantially in planes parallel to the axis of the formation and thus assist the 5 warp and weft in resisting tensional stresses in the articles produced.

Obviously the auxiliary strand *a* may be in the form of a thread, yarn or ribbon without departing from the nature of this 10 invention and if so desired a plurality of such threads, yarns or ribbons may be simultaneously applied.

I claim:

1. An improved sheet material comprising warp threads and weft threads interwoven to form a fabric and auxiliary threads overlaid on the warp threads and weft threads in angular relation to both warp threads and weft threads and means 20 for maintaining the auxiliary threads in predetermined position.
2. In an improved sheet material as

claimed in claim 1 the use of an agglutinant with which the warp threads, weft threads and auxiliary threads are impregnated, said 25 agglutinant enabling close and intimate association between the warp, weft and auxiliary threads being obtained by the application of pressure.

3. An improved compound sheet material 30 in which an auxiliary thread is disposed at 45° to and laid over the warp and weft threads and arranged at right angles to the cut edges of the material, substantially as and for the purposes described. 35

In testimony whereof I have signed my name to this specification in the presence of the subscribing witnesses.

ARTHUR RONALD TRIST.
